HEINRICH SCHLEGEL, OF DUISBURG-RUHRORT, GERMANY.

MEANS FOR THE PRODUCTION OF BUILDING BLOCKS.

Application filed July 7, 1926, Serial No. 120,920, and in Germany October 8, 1924.

This invention relates to a method and means for the production of blocks, particularly light concrete blocks, by a rolling operation.

5 It has hitherto been usual to produce concrete stones or bricks in single moulds by stamping the same manually, or by means of a stamping machine. Large building blocks are extremely difficult to produce in 10 a pressing operation, since on account of the friction of the material against the sides of the mould the pressure does not extend evenly to the bottom of the mould, so that the blocks at the bottom are considerably 15 weaker than at the top. In producing artificial bricks in a beating operation the difference in strength is still greater.

The method employed according to the invention, particularly as regards the production 20 of light concrete blocks such as are used in the building of houses, differs from the known method by the fact that the material employed, which may consist of granulated blast-furnace slag with the addition 25 of burnt lime and cement and suitable binding agents, is worked upon in layers by means of rollers in a high, closed mould to form an elongated slab, whereby the roller acts under its own weight, and the height 30 thereof from the bottom of the mould is varied as the height of the slab increases. In this manner slabs or blocks (afterwards cut to size) of considerable height, but nevertheless perfectly regular throughout, are 35 formed, since upon the rolling operation the roller does not only move over the material, but at the same time also displaces the surface thereof forming gaps or breaks therein, which are filled or plugged up by the 40 consecutively applied layer.

According, therefore, to the invention, elongated slabs are produced in a mould by rolling out layers of material one above the other, the arrangement being such that the 45 face walls of the mould are increased in height in conformity with the increasing height of the slab by the application of additional wall portions, the rollers also being varied in their distance from the bottom 50 of the mould by reason of the fact that as fresh material is introduced the said rollers

are moved out of the mould and on to an adjustable platform, and lifted together with the latter.

The material is introduced into the mould 55 in the form of single horizontal layers as required for each rolling operation, and the individual layers compressed, i. e., rolled out by means of one or more sets of rollers, which are movable in the mould and act 60 by reason of their own weight, until the desired height and density of the block has been attained. The rolling operation, and accordingly the time required therefor, may be reduced by increasing the number of 65 rollers. The density of the block may be regulated by variation in the weight or diameter of the rollers. The side walls of the elongated mould are initially provided with the correct height and width; the length 70 of the mould may be selected as desired. It is desirable, however, to form in one mould a composite elongated slab or block, which is then cut to the desired lengths. The width of the rollers and the interior 75 width of the mould are equal, so that the rollers work upon the surface of the material over the whole width of the mould. The rollers may be driven by any motive power through the medium of suitable traction means, the direction of movement being reversed at the end of each movement by reversal of the driving means.

Since the material in the mould increases 80 in height as additional layers are introduced, it is necessary to also lift the rollers step by step, and to return the same again to the commencing position after the block has been completed. This is effected by 85 means of a lifting table mounted at each end of the mould, each table having a vertically movable platform for the rollers. With the variation in the height of the rollers it is also necessary to allow for variation 90 in the height of the driving means for the same. In place of a fixed drive the operation of the rollers may also be effected by means of a motor mounted on the roller carriage.

The two face walls of the mould also require 100 to be increased in height in order to allow for increased height of the material,

and the said walls accordingly consist of individual parts which slide in guideways on both sides.

Any decorative layers required may be 5 rolled out together with the concrete. After the material has hardened and after removal of the walls of the mould the exposed slab or block is cut into the desired lengths, for example, in the known manner by sawing.

10 The slab or block may be rolled out either edgewise or flat, or a number of slabs or blocks may be produced superimposedly, the individual slabs being held separate from each other by the provision of intermediate 15 layers, for example of thick paper.

Since during the rolling operation the roller not only rolls over the material, but is also displaced along the same, so that the surface of the material is provided with a 20 corrugated form and breaks are caused automatically therein which are filled out by the consecutive layer applied, the individual layers of the slab or block are, in a manner of speaking, plugged together.

25 The extent of this plug-like connection of the superimposed layers may be still further increased if the rollers, instead of having a smooth surface, are provided on the periphery with teeth, studs, ribs or the like 30 which, upon the rolling operation, are pressed into the material and cause recesses to be formed, which are filled out by the material of the consecutively applied layer, thus increasing the anchorage and plugging 35 effect between the two layers. If all the rollers are mounted in one carriage or frame, each roller may be provided with such indenting means on the periphery, or merely the one or other roller need be thus formed.

40 The recesses or indents produced may be of any desired shape, size or depth in accordance with the means provided on the rollers for causing the same. Simple studs, spikes or other projections, for example in 45 the form of teeth, may be used, or the periphery of the roller may be ribbed or fluted. The chief consideration is that the surface of the material, by the construction of the rollers, be provided with recesses which are 50 filled out by the material of the successive layer, in such manner that the superimposed layers are intimately connected.

Vice versa, the arrangement may also be 55 of such kind that, in place of a fixed mould and movable rollers or roller carriage, the rollers are made to be stationary and the mould caused to reciprocate in relation to the rollers, whereby the workman supervising the operations is able to remain at the 60 point where the rollers are located.

A device for carrying out the method according to the invention is illustrated by way of example in the accompanying drawing.

65 Fig. 1 is a front view of the device, partly

in section and showing merely the left-hand portion.

Fig. 2 is a section through the mould showing the rollers, drawn on larger scale.

Fig. 3 is a cross-section thereto, and

Fig. 4 a plan.

The mould comprises the two side walls 5 with the face walls 9, which latter may be increased in height as the block is formed. The material 6 is introduced into the mould 75 in individual layers, for which purpose may be used a feed carriage made to travel in a longitudinal direction along the top of the mould. This carriage supplies the material in layers which are as even as possible. 80 The individual layers of material are worked upon by cylindrical rollers 7. For accelerating the operation it is possible in place of one roller to use two or more rollers, which may be united in a carriage. 85

The rollers are driven by means of a stationary motor in conjunction with a suitable traction means, or by means of a motor which is directly connected with the rollers or roller carriage. In the embodiment illustrated in the drawing the traction means comprises a cable or the like 8 which on both sides of the face walls 9 is passed over pulleys 10, 11, 12 and 13. The stationary motor acts upon the axle of the fixed wheel 12. Since the horizontal cable 8 also requires to be lifted together with the roller carriage as the height of the material increases by the application of additional layers, the pulleys or guide rolls 10 and 13 are mounted in a vertically movable carriage or the like 14, which may be adjusted in accordance with the height of the carriage for the rollers 7. The weight of the carriage 14 is compensated by means of a cable 105 15 in conjunction with a stationarily mounted roll 16 and a counter-weight. The cable 8 is accorded the necessary tension by means of a counter-weight 17, which acts by means of the cable 18 and the fixed roll 19 110 upon the loose roll 11.

The cable 8 is connected with its two ends to the carriage for the rollers 7, or is made to be of the endless kind and passed over the roll 20 mounted on the said carriage. 115 The roll 20 is fixed during the rolling operation, so that the same is unable to rotate. The cable 8, which is passed several times about the roll 20, is accordingly firmly connected with the roller carriage 7, and pulls 120 the same. If on the other hand the coupling between the carriage 7 and the roll 20 is released, so that the roll is able to freely rotate on the carriage frame, the cable 8 runs loosely over the rotating roll 20 and the carriage remains at rest. The adjustable roll 20 accordingly allows the cable 8 to 125 continue to run without the necessity of having to pull the heavy rollers, for example, when adjusting the carriage 14 as 130

regards height. On the other hand, it is possible to move the roller carriage 7 when the cable 8 is not in action by rotation of the roll 20 by means of a crank, the cable 8 being wound on to the roll 20.

Since, as mentioned above, the width of the rollers 7 should conform with the width of the mould, in order that the complete surface of the material be acted upon by the rollers, the frame of the roller carriage is mounted at the centre, in such manner that on both the front as well as the rear axle are provided two rollers 7, between which is provided a space for the carrying member, which, composed for example of strong sheet metal, possesses in the space between the front and rear rollers 7 a frame for smaller intermediate rollers 21, the latter working upon the material along the centre which has not been touched by the main rollers on account of the gap between them. In the form of embodiment shown in the drawing the cable 8 engages the rollers centrally, in order to avoid any tendency to tilt. The cable 8 is passed through the space between the main rollers, and over rolls at the ends of the carrier.

Since it is also necessary to lift the roller carriage as the material in the mould increases in height, an adjustable platform 22 is provided in front of each end wall of the mould, this platform, in the case of the embodiment shown, being moved by means of a threaded spindle.

The end walls 9 of the mould 5 also require to be increased in height in conformity with the increase of material. For this purpose the said walls are composed of individual parts which slide in guideways on both sides, and to which additional sections may be added in the said guides as the height of the material increases.

After the slab or block has set, i. e., become hardened, the same is removed from the mould and cut to the required lengths.

For the purpose of improving the plug-like connection between the superimposedly rolled layers of material, the rollers 7, in the case of Figs. 2-4, are not smooth, but provided on the periphery with projections, studs, teeth, ribs or the like 23 which, upon the rolling operation, produces indentations or recesses in the surface of the material, these indentations or recesses 24 being filled out by the consecutively applied layer and thus causing an anchorage between each successive pair of layers.

As stated above, the arrangement within the mould may also be reversed, i. e., the rollers may be made stationary and the mould caused to perform a reciprocatory movement, moving the material along the rollers.

What I claim as new and desire to secure by Letters Patent is:

1. In a plant for the production of slabs or blocks in successive layers, the provision of a mould into which the material is introduced in successive layers, rollers for compressing the material after the introduction of each layer, means for actuating the rollers comprising a motor, a cable passed over guide rolls and connected with the said rollers, and counter-weights for tensioning the said cable, and means for adjusting the height of the rollers to conform with the height of the material in the mould.

2. In a plant for the production of slabs or blocks in successive layers, the provision of a mould into which the material is introduced in successive layers, rollers for compressing the material after the introduction of each layer, means for actuating the rollers comprising a motor, a cable passed over guide rolls and connected with the said rollers, means for reversing the said actuating means when the rollers are at each end of the mould, and counter-weights for tensioning the said cable, and means for adjusting the height of the rollers to conform with the height of the material in the mould.

3. In a plant for the production of slabs or blocks in successive layers, the provision of a mould into which the material is introduced in successive layers, rollers for compressing the material after the introduction of each layer, means for actuating the rollers, and means for adjusting the height of the rollers to conform with the height of the material in the mould, comprising an adjustable platform at each end of the said mould, the said platform being adjusted by means of a threaded spindle.

4. In a plant for the production of slabs or blocks in successive layers, the provision of a mould into which the material is introduced in successive layers, means for adjusting the height of the end walls of the said mould comprising separate parts sliding in lateral guides, the said parts being added as required, rollers for compressing the material after the introduction of each layer, means for causing the said rollers to act upon each layer, and means for adjusting the height of the said rollers to conform with the height of the material in the mould.

5. In a plant for the production of slabs or blocks in successive layers, the provision of a mould into which the material is introduced in successive layers, means for adjusting the height of the end walls of the said mould comprising separate parts sliding in lateral guides, the said parts being added as required, rollers for compressing the material after the introduction of each layer, projections on the periphery of said rollers for causing recesses in the surface of each layer, said recesses being filled out by the material of the successive layer, means for actuating

the said rollers comprising a motor, a cable passed over guide rolls and connected with the said rollers, and counter-weights for tensioning the said cable, means for reversing the said actuating means, and means for adjusting the height of the said rollers to conform with the height of the material in the said mould as the successive layers are

introduced, comprising an adjustable platform at each end of the said mould, the said platform being adjusted by means of a threaded spindle.

In testimony whereof I have affixed my signature.

HEINRICH SCHLEGEL.
